UNITED STATES PATENT OFFICE.

JOHN THOMAS WARNE, OF BURNABY, BRITISH COLUMBIA, CANADA.

LOCK.

1,274,477.

Specification of Letters Patent.

Patented Aug. 6, 1918.

Application filed October 24, 1917. Serial No. 198,306.

To all whom it may concern:

Be it known that I, JOHN THOMAS WARNE, a subject of the King of Great Britain, and a resident of the municipality 5 of Burnaby, in the Province of British Columbia, Canada, have invented certain new and useful Improvements in Locks, of which the following is a specification.

My invention relates to improvements in 10 locks, and the object of my invention is to provide a lock having means incorporated therewith for locking the lock bolt against unauthorized retraction so that it cannot be readily opened except with the proper key 15 provided for it, and which lock is simple in construction and efficient in operation.

I attain this object by the construction illustrated in the accompanying drawings in which—

20 Figure 1 is a view of the interior of the lock.

Fig. 2 is a cross section taken on the line a—b of Fig. 1.

Similar figures of reference indicate similar parts throughout the several views.

1 indicates the lock casing having a removable side plate 2 and provided with a keyhole 3, adjacent to which keyhole is arranged a similar construction to that found 30 in locks in present use, such construction being indicated generally at 4 in Fig. 1 and consisting of the usual elements coöperating with the wards of the key bit with which the lock is supplied to prevent the turning in 35 the lock of any but the proper key, in fact, the lock casing, with its key and tumbler arrangement may be made substantially the same as that of any well-known lock construction.

40 5 indicates the locking bolt, which is slidably mounted for longitudinal movement in the casing, being shown in the projected locking position in Fig. 1. The bolt 5 is provided on its upper edge with a plurality of rearwardly facing notches 6 and on its lower edge with a plurality of teeth 7, with which teeth engages normally a pinion 8, which pinion is mounted on and secured to the transverse rotatable shaft 9, 50 this shaft being provided with the usual door knobs 10 on each end and rotated thereby, one knob only being shown, in Fig. 2, and indicated dotted in Fig. 1, from which it will be seen that the lock bolt 5 may 55 be projected and retracted to lock or unlock the door by turning knob 10 in the required

direction, the projecting of the bolt, however, being effected without the necessity of turning the knob by means of a spring 11, which spring is disposed between the inner 60 end of the bolt and the end plate of the casing 1 and is compressed by the bolt when retracted. 12 and 13 indicate slots formed in the bolt 5 and coöperating with suitably secured pins 14 and 15, by means of which 65 the bolt is guided in its longitudinal travel.

In order to prevent unauthorized opening of the lock a pawl 16 is provided, which pawl is fulcrumed as at 17, the long end 18 normally engaging one of the notches 6 70 when the bolt is projected into the locking position, its short end 19 extending adjacent the keyhole and disposed in the path of the key bit so that it may be contacted thereby as it is turned in the lock, in either direction. 75 20 and 21 indicate spring members arranged to form a pair of spring jaws directly above the long end of the pawl, between which jaws the pawl is held clear of contact with the bolt when the same is to be retracted. 22 80 indicates the key, the bit of which is shown engaging the short end 19 and on the point of raising the long end 18 clear of the notch with which it is engaged.

The operation of my device will be apparent. Assuming that the parts are as shown in Fig. 1, the bolt being out and in the locking position, it will be seen that the bolt is held against inward movement by the engagement of the pawl 16 with the notch 90 6 and that no movement of the knob 10 can move the bolt until the pawl is raised clear of the same, therefore, in order to allow the bolt to be retracted it is necessary to insert the key, which must necessarily be the 95 proper one, in the keyhole, and turn it in the direction of the arrow until the bit of the key contacts with, and bears down, the short end 19 of the pawl, thus raising the long end 18 and forcing it up between the 100 spring jaws formed by the members 20 and 21, between which it is held clear of the notches 6, as indicated dotted in Fig. 1. The bolt may then be retracted or projected by means of the knobs in the usual manner. 105

To lock the bolt again when it is in the locking position the key is turned in the opposite direction to contact with, and carry up, the short end of the pawl, thereby forcing the long end clear of the spring jaws 110 and allowing it to drop into engagement with the notch 6.

It will be seen, therefore, that I have devised a simple and effective lock which is incapable of being readily opened unless by the proper key provided for its authorized manipulation.

What I claim as my invention is:

1. In a lock, the combination with a casting having a key hole, of a key bit, a sliding bolt having upper edge notches and lower edge teeth, an independent pawl pivoted off center located between the bolt and key bit having its long end normally coacting with said notches and its short end disposed to be contacted by the key bit so as to raise or lower the notch engaging end, and a pinion engaging the said teeth by the rotation of which the bolt may be projected or retracted.
- 10 2. In a lock, the combination with a casting having a keyhole, of a sliding bolt having upper edge notches and lower edge teeth, a suitably fulcrumed pawl having one end co-acting with the said notches and its other end disposed to be contacted by the key bit so as to raise or lower the notch-engaging end, spring jaws between which the notch-engaging end is forced when raised, and a
- 15
- 20
- 25

pinion engaging the said teeth by the rotation of which the bolt may be projected or retracted.

3. In a lock, the combination with a casting having a key hole, of a sliding bolt mounted for projection or retraction and provided with upper edge notches, and a straight flat pawl suitably fulcrumed intermediate of its length having its long end co-acting with said notches and its short end disposed to lie in the path of the key bit so that the notch engaging end may be raised or lowered by direct contact of the key bit with the short end.

4. In a lock, the combination with a casting having a keyhole, of a sliding bolt mounted for projection or retraction and provided with upper edge notches, and a suitably fulcrumed pawl having one end co-acting with the said notches and its other end disposed to lie in the path of the key bit, so that the notch engaging end may be raised or lowered by direct contact therewith.

Dated at Edmonds, B. C., this 4th day of Oct., 1917.

JOHN THOMAS WARNE.
